UNITED STATES PATENT OFFICE

1,943,443

METHOD OF COATING SHEET MATERIAL

Charles O. Kilham, Beverly, Mass., assignor to
United Shoe Machinery Corporation, Paterson,
N. J., a corporation of New Jersey

Original application May 10, 1930, Serial No.
451,451. Divided and this application Febru-
ary 6, 1933. Serial No. 655,368

6 Claims. (Cl. 12—146)

This invention concerns the coating of sheet material, and is herein exemplified with special reference to the coating of sheet material which has its margins beveled or otherwise made thinner than the body of the sheet.

5 Machines of the character described in Letters Patent of the United States No. 1,656,346, granted January 17, 1928, upon an application of John W. Cosgrove, are designed to operate upon material in the form of sheets, of which the opposite faces are substantially parallel throughout. In the manufacture of shoes, for example, work is sometimes encountered which, instead of having such parallel faces, is thinner at the margins. 10 Thus, rubber soles for shoes commonly have peripheral bevels at the tread side. When such soles are freshly cut, the face which is to be cemented to the insole may be plane; but, as they age, the margin tends to curl toward the beveled side, making it difficult to apply cement properly to this thin, distorted margin. An object of the present invention is to provide for coating, in a substantially uniform manner and expeditiously, entire faces of sheets having such 15 reduced margins.

For the attainment of this object, my invention contemplates a method of coating which may consist in applying a coating progressively to one face of a sheet of material while the sheet 30 is bent about a line substantially parallel to the direction of progress, thereby stretching the outer face, the coating being applied to the face which is under greater tension. Such stretching draws the margin toward the coating instrumentality, 35 rendering the surface fully accessible. Considering the invention in another aspect, the sheet will be made convex upon the face to be coated, as by stretching and, bending it, for example by pressing it against a concave surface which has 40 been supplied with a coating substance.

In performing the method above set forth, I may utilize an apparatus of the type disclosed and claimed in an application Serial No. 451,451, filed May 10, 1930, in my name, and of which this 45 application is a division. In that apparatus, an applying roll, with its applying surface curved longitudinally of the axis of rotation, operates in a receptacle for a coating substance and has cooperating with it a rotatable pressure roll with 50 its surface oppositely curved. The applying roll is preferably concave and the pressure roll convex. Thus, when the work is pressed against the concave applying roll by the convex pressure roll, there is obtained the desired stretching of 55 the surface to be coated and the simultaneous

application of the coating substance. Such an apparatus, useful but not essential in carrying out my improved method, is illustrated in the accompanying drawing, in which

Fig. 1 shows such a machine in broken side elevation;

Fig. 2 is a transverse section on the line II—II of Fig. 1;

Fig. 3 is a fragmentary view showing, on an enlarged scale, a portion of the sole and the rolls, as in Fig. 2; and

Fig. 4 is an enlarged cross-section through a rubber sole the edges of which have curled from their original shape, which latter is shown in dotted lines.

70 For the general construction of the present apparatus and for certain details which have no particular bearing upon my invention, reference may be had to the previously mentioned patent. A tank or receptacle 10, adapted to contain the 75 cement or other coating substance to be applied, has journaled in its side walls a horizontal shaft 12 for a rotatable applying roll 14, the lower portion of which lies in the contained adhesive. The applying surface of this roll is preferably 80 concave, being gradually curved longitudinally of its periphery from ends of maximum diameter to a reduced central portion. The roll is rotated, in the direction indicated by the arrow in Fig. 1 of the drawing, by connections at 16 85 through a counter-shaft 17 to a motor, and is supplied with work-pieces over a table or conveyor 18, the coated pieces being removed by a conveyor 20 at the opposite side of the roll 14.

85 To hold the work in contact with the roll 14 90 during the progressive coating operation, and to aid in its advance, an upper pressure roll 22 is rotatable about the axis of a shaft 24 parallel to and vertically aligned with the shaft 12. The shaft 24 is journaled in side arms of a frame 26 95 pivoted at 28, 28 upon a bridge 30 rising from the sides of and extending across the top of the tank. The roll 22 is convex, its longitudinal curvature being substantially concentric to the surface of the roll 12. As illustrated, it is in three independent sections. That at the center, to which the numeral 22 has been applied, is fast upon the shaft 24. The adjacent sections 32, 32, at its opposite sides, are loose upon the shaft. The 100 ends of the sections operate substantially in contact with one another, the convex surface of the roll 22 being thus practically unbroken. Extending upwardly from the frame 26, at opposite sides of the bridge, are two projections 34 and 36, the 110

former having interposed between it and the bridge a spring 37, which exerts its force constantly to urge the roll 22 toward the applying roll 14. Threaded through the other projection 5 is a screw 38, bearing at its inner extremity against the bridge. By differently positioning this screw, the normal separation between the rolls may be varied, thus adapting the apparatus to operate to the best advantage upon sheets of 10 different thicknesses. The roll 22 is rotated oppositely to the roll 14, the central section having the same peripheral speed as such applying roll. This is accomplished by gearing 40 joining the shaft 24 to a counter-shaft 42 horizontally aligned 15 with the pivotal points 28 of the frame 26, and gearing 44 between said counter-shaft and the shaft 17.

In utilizing this apparatus to carry out my improved method, and assuming that rubber soles S beveled to form an inclined edge 46 about 20 their tread faces T are to be cemented upon the larger face 48 opposite to the tread face, the operator feeds the work-pieces successively between the oppositely rotating applying roll 14 and the pressure roll 22 from the table 18, the face opposite the tread being down. As each sole is advanced through the rolls by their rotation, the upper roll presses it into the concavity of the applying roll, bowing it downwardly and outwardly 25 about a line substantially parallel to the direction of progress and stretching the lower larger face 48 transversely as the coating is applied. This strain upon the material draws down the thin margin formed by the convergence of the beveled edge with the larger face of the sole at 30 50, so that, even if it is curled over toward the tread face T, as indicated in Fig. 4, or is in an uneven wave form, the tension holds it firmly against the applying surface, which will lay upon 35 the lower face 48 a substantially uniform coating 40 extending to the very edge. If a sole enters the rolls at one side of their longitudinal centers, no appreciable retarding effect is produced by those more slowly rotating peripheral portions of the pressure roll which are of less diameter than the 45 central portion, since the two outer sections 32, 32 are not driven and can turn with the sole as it travels beneath them. The departure of the 50 central driven portion of the roll 22 from the cylindrical form is not sufficient to impart to the work-pieces an angular deflection, so their travel is along a substantially straight line. This freedom of the end sections of the pressure roll in 55 no way impairs its ability to maintain a proper contact of the surface being cemented with the applying roll. The sole operated upon thus

emerges from between the rolls, upon the conveyor 20, with its entire lower face cemented.

Having thus described my invention, what I claim as new and desire to secure by Letters Patent of the United States is:

1. The method of coating a piece of sheet material having opposite thin marginal portions which consists in applying a coating progressively to one face of the material and simultaneously bending the sheet about a line substantially parallel to the direction of progress thereby to stretch one face more than the opposite face, the coating being applied to that surface which is under greater tension.

2. The method of coating unattached soles having beveled edges, which consists in supplying a concave surface with a coating substance, pressing a sole against the concavity with the inclined edge away from the coated surface, and moving the sole over said surface.

3. The method of coating a sole having beveled edges and with one face which is larger than the other and terminates in a thin margin, which consists in bending said sole transversely to stretch the larger face, and simultaneously applying a coating to the whole width of the larger face.

4. The method of coating a sole having its edge beveled to provide one face larger than the other with the inclined edge forming a thin margin around the larger face, which consists in supplying a concave surface with a coating substance, and exerting pressure against the smaller face of such a sole to force the larger face including its thin margin against said coated concave surface.

5. The method of coating a sole having one face larger than the other and which faces are joined by a sloping edge surface, which consists in supplying a concave surface with a coating substance, pressing the larger face against the concave surface, thereby to stretch the larger face to bring all portions thereof firmly into contact with said concave surface, and moving the sole over said coated concave surface while maintaining said stretched condition.

6. The method of coating soles having beveled edges which consists in bending said soles transversely between oppositely curved surfaces, thereby to stretch one face of each sole to cause said face including the margin thereof to contact firmly with one of the surfaces, supplying a coating substance to said latter surface, and causing relative movement between said surfaces and the sole to coat one face of the sole while maintaining the bent relation thereof.

CHARLES O. KILHAM.
